UNITED STATES PATENT OFFICE.

WILLIAM E. STEVENS, OF NEW HAVEN, CONNECTICUT, ASSIGNOR TO SARGENT & CO., OF SAME PLACE.

DESIGN FOR A COFFIN-SCREW.

SPECIFICATION forming part of Design No. 15,428, dated September 23, 1884.

Application filed July 30, 1884. Term of patent 14 years.

To all whom it may concern:

Be it known that I, WILLIAM E. STEVENS, of New Haven, in the county of New Haven and State of Connecticut, have invented a new Design for Coffin-Screws; and I do hereby declare the following, when taken in connection with the accompanying drawing and the letters of reference marked thereon, to be a full, clear, and exact description of the same, and which 10 said drawing constitutes part of this specification, and represents a side view.

This design relates to that class of coffin-screws in which the head represents a cap as drooping down around the body of the head; 15 and it consists in the configuration as described, and shown in the accompanying illustration.

A represents the body of the screw, and B the cap. The cap is of hemispherical shape, its lower edge consisting of scallops *a*, alternating with points *b*. On the surface of the 20

cap is the representation of a festoon of fringe hanging over the edges of the scallops, and an underlying festoon of fringe on the points, the surface within the festoon representing lace, as shown.

The essential feature of my design is the cap having the lower edge formed of scallops alternating with downwardly-projecting points. 25

I claim—

The herein-described design for a coffin-screw head, consisting of a body with a cap represented as drooping around the body, the lower edge of the cap representing scallops alternating with downwardly-projecting points, as shown in the accompanying illustration. 30

WM. E. STEVENS.
